UNITED STATES PATENT OFFICE.

JOHN WALTER, OF YATES CENTER, KANSAS.

SICKLE-HOLDER.

No. 805,894.

Specification of Letters Patent.

Patented Nov. 28, 1905.

Application filed February 23, 1905. Serial No. 246,892.

To all whom it may concern:

Be it known that I, JOHN WALTER, a citizen of the United States, and a resident of Yates Center, in the county of Woodson and 5 State of Kansas, have invented a new and Improved Sickle-Holder, of which the following is a full, clear, and exact description.

The purpose of the invention is to provide a sickle-holder especially adapted for attachment to the frame of a grindstone for the purpose of holding the knives in engagement with the stone during the grinding process.

Another purpose of the invention is to provide a device of the character described which 10 will be simple, durable, economic, and readily applied, the device being so constructed that the sickle-bar can be readily introduced, adjusted in the device, and locked in adjusted position or removed therefrom, and, further, 15 to provide a construction whereby the sickle-holder can be adjusted to any desired angle or to any bevel and can be vertically adjusted to accommodate it to any size of stone and also moved forward and backward to impart 20 the necessary movement to the knives over the stone.

The invention consists in the novel construction and combination of the several parts, as will be hereinafter fully set forth, 25 and pointed out in the claims.

Reference is to be had to the accompanying drawings, forming a part of this specification, in which similar characters of reference indicate corresponding parts in all the figures.

35 Figure 1 is a perspective view of the improved sickle-holder applied to a grindstone. Fig. 2 is a plan view of the device and a portion of its supporting-frame. Fig. 3 is a vertical section through the device, taken practically on the line 3-3 of Fig. 2, a vertical portion through a portion of the grindstone-frame, and a side elevation of a portion of the stone to which the device is applied. Fig. 4 is a vertical section taken substantially on 40 the line 4-4 of Fig. 2. Fig. 5 is a vertical transverse section taken substantially on the line 5-5 of Fig. 2, and Fig. 6 is a detail perspective view of the adjustable end guide for the sickle-bar.

50 A represents the frame of an ordinary grindstone, B the stone, and C represents bearings which are secured on the upper face of the side beams 10 of the frame at an end of said beams. The body member D of the holder, 55 or the member which receives and carries the sickle-bar 11 and its knives 12, is made of

any desired length and is intended to extend across the periphery of the stone B. In the construction of the said body a bar member 13 is employed, to the top of which a rearwardly-extending arm 14 is secured, and below the arm 14 a clamp 15 is adjustably and removably mounted in the bar member 13, held in adjusted position by a set-screw 16, passed through the arm 14 and bar member 60 13 to an engagement with the inserted portion of the clamp. The head of this clamp is made to engage with the forward longitudinal edge of the sickle-bar 11 and holds the sickle-bar from moving forward without interfering with the end or sliding movement 65 of the sickle-bar, as is shown in Figs. 1 and 2.

One end of the sickle-bar 11 is loosely passed between upper and lower guide-fingers 17 and 18, which extend forward from one end 70 portion of the bar member 13, the opposing faces of which fingers are more or less recessed to assist in preventing the forward movement of the sickle-bar 11. At the opposite end of the bar member 13 of the body 75 D at its back a longitudinal recess 19 is made, and in this recess 19 the shank 20 of an adjustable guide d is located, the head of the said guide d being provided with a forwardly-extending pin 21, upon which pin an end portion of the sickle-bar 11 is made to rest. The guide d is adjustably held in position by producing a longitudinal slot 22 in its shank 20 and passing a set-screw 23 through the slot and into the bar member of the body, as is 80 85 shown in Fig. 2, the said guide d being shown in detail in Fig. 6.

The arm 14, extending from the bar member 13 of the body D, is adjustably attached to a forwardly-extending flat member 24 of a head E by means of a bolt 25 or its equivalent, so that the body D has horizontal adjustment on said head, and the head E is swiveled or mounted to turn upon a cap F, 90 said cap having a forwardly-extending cylindrical member 26, which enters a correspondingly-shaped socket 27 in the said head, as is shown in Fig. 3, and the head E is held in adjusted position on the cap F by a set-screw 28, passing through the head to an engagement with the said member 26 of the cap. Thus it will be observed that the body D of the holder can be adjusted to any angle with reference to the stone to grind any desired bevel at the cutting edges of the knives. The 95 cap F is provided with downwardly-extending end lugs 29 in order that a standard G 100 105

may have a pivotal or hinged connection with the cap, which standard is adapted to be connected with the frame A of the grindstone in a manner to be hereinafter described.

5 The pivotal or hinged connection between the standard G and the cap F is effected by providing the standard at its upper end with upwardly-extending lugs 30, which are loosely passed up between the lugs 29 of the 10 cap and by loosely passing a pin or bolt 31 through the lugs of the cap and the lugs of the standard, as is shown in Fig. 4. This connection enables the body D of the holder to be operated vertically to and from the 15 stone in order to remove a sickle-bar or place one in position.

A grooved projection 32 is formed upon the inner or forward face of the standard G, and the groove of the said projection receives 20 the slotted shank 33 of a pivotal connecting member H, which member is provided with base-pins 34, adapted to be mounted in the bearings C on the frame A of the grindstone. An adjustable connection is effected between 25 the hinge connecting member H and the standard G by means of a bolt 35, passed through the standard and through the slot in the shank 33, as is illustrated in Figs. 3 and 4. The pivotal connecting member H is pref- 30 erably made of stout wire or bar metal bent to the shape desired.

It will be observed that by reason of the pivotal connection between the standard G and the frame A of the grindstone and the 35 pivotal connection between the cap F and the standard the body D, carrying the sickle-bar 11, can be moved backward and forward to bring the cutting edges of the knives their full length in reciprocating engagement with 40 the grindstone. It will also be observed that by reason of the vertical adjustment between the pivotal connecting member H and the standard G the device can be lengthened or shortened to accommodate it to different 45 sizes of grindstones. The sickle-bar 11 is firmly held in position at the body D while a knife is being ground by securing a horizontal forwardly-extending rest-arm 37 to the bar member 13 of the said body D, against 50 the under face of which arm a knife 12 of the sickle-bar 11 has bearing, and pivoting a yoke-clamp 38 to the outer end of the said arm, one member of which extends above the arm and the other below it, the under member being 55 somewhat upwardly curved, the knife just referred to occupying a position below the lower member of the clamp and the under face of the rest-arm, as is shown in Fig. 3. The knife which is thus clamped is the one 60 adjacent to the knife being acted upon by the stone.

A lever 39 is employed in connection with the clamping-yoke 38 to carry the lower member of the yoke upward to hold a knife 65 firmly against the rest-arm 37 when another

knife is being sharpened and to permit said lower member of the yoke-clamp to drop when the sickle-bar is to be shifted, introduced, or removed.

The handle end of the lever 39 extends 70 rearwardly over the bar member 13 of the body D, and its opposite or forward end is pivotally attached to the end portion of the upper member of the clamping-yoke 38, as is shown at 40 in the drawings, and at the pivotal end of the lever 39 a downwardly-extending cam-finger 41 is attached to or is made integral with the lever, which finger when the handle end of the lever is pressed downward has locking bearing upon the upper face of the rest-arm 37 and at such time raises the upper member of the yoke-clamp, thereby carrying the lower member also upward to tight locking engagement with the knife; but when the handle of the lever 39 is 85 carried upward and forward the cam-finger 41 will be out of engagement with the rest-arm 37, whereupon the lower member of the clamping-yoke will through gravity drop down and free the knife with which it en- 90 gaged.

Having thus described my invention, I claim as new and desire to secure by Letters Patent—

1. In sickle-holding attachments to grindstones, a body member, guide or check devices for the sickle-bar carried by the said body member, a rest-arm also carried by the said body member, a clamping-yoke pivoted on the rest-arm and extending above and below said arm, and a lever for operating the clamping-yoke. 95

2. In sickle-holding attachments to grindstones, a body member, guides and check devices for the sickle-bar, a rest-arm extending from the said body member, a yoke-clamp pivoted on the rest-arm extending above and below said arm, a lever pivotally attached to the yoke-clamp above the rest-arm, provided with a downwardly-extending cam-finger for engagement with the rest-arm, a support, and a pivotal connection between the said support and the said body member. 100

3. In sickle-holding attachments to grindstones, a body member provided with guide and locking means for a sickle-bar, a head, a pivotal connection between the said head and the said body member, the body member being mounted to turn on the head, a pivoted and adjustable support, a swivel connection 115 between the said support and the said head, and means for locking the body member and the head in adjusted positions. 120

4. In sickle-holding attachments to grindstones, a body member provided with guide and locking means for a sickle-bar, a head, a pivotal connection between the head and the body member, a pivoted and adjustable support, a cap pivoted to said support, a swivel 125 connection between the said head and the 130

said cap, and means for locking the body member and the head in adjusted position.

5. In sickle-holding attachments to grindstones, a body member, guide and locking devices carried by the said body member, a rearward extension from said body member, a head, a pivotal connection between the said extension from the body member and the head, a cap, a swivel connection between the cap and the head, a standard pivotally connected with the under portion of the cap, the standard being at an angle to the said cap, the head and the body member, a hinge connecting member adjustable upon the standard, the said hinge connecting member being provided with oppositely-extending pins, bearings for the said pins, and means for securing the body member and the head in adjusted position.

10 6. In a sickle-holding attachment for grindstones, a body member, a clamp carried by the body member for engaging the forward edge of the sickle-bar, a fixed guide at one end of the body member, and an adjustable guide at the other end of said body member.

15 7. In a sickle-holding attachment for grindstones, a body member, guides on the body member in which a sickle-bar is free to slide endwise, a rest-arm projecting forwardly

from the body member, a hook-shaped clamp pivoted to the forward end of the rest member and extending above and below the rest-arm, and a cam-lever pivoted to one end of the clamp.

8. In a sickle-holding attachment for grindstones, a body member, means for clamping a sickle-bar to said body member, a head pivoted to the body member and provided with a socket at its rear end, a standard, and a cap pivoted to the standard and provided with a member fitting in the socket of the head.

9. In a sickle-holding attachment for grindstones, a body member, means for clamping a sickle-bar to the body member, a head pivoted to the body member, and provided with a socket in its rear end, a standard, a cap pivoted to the standard and provided with a member fitting in the socket of the head, and a hinge connecting member adjustably secured to the standard.

In testimony whereof I have signed my name to this specification in the presence of two subscribing witnesses.

JOHN WALTER.
